UNITED STATES PATENT OFFICE.

JOSEPH WARREN KESSEL, OF BROOKLYN, NEW YORK.

CLIP.

Application filed January 25, 1921. Serial No. 439,839.

To all whom it may concern:

Be it known that I, JOSEPH WARREN KESSEL, a citizen of the United States, residing at Brooklyn, in the county of Kings and State of New York, have invented a new and useful Clip, of which the following is a specification.

This invention relates to pen or pencil clips, it being the object of the invention to provide a clip having means to cause the same to firmly grip the pocket of the user, to eliminate any possibility of the clip and article supported thereby from becoming disconnected and lost.

15 A further object of the invention is to provide a device of this character which will permit the clip and article supported thereby to be readily and easily positioned.

With the foregoing and other objects in view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed, without departing from the spirit of the invention.

Referring to the drawings:

30 Figure 1 illustrates a side elevational view of a pen cap supplied with a clip constructed in accordance with the present invention.

Figure 2 is a detail view of the gripping 35 end of the clip.

Figure 3 is a plan view of the gripping end of the clip.

Figure 4 is a sectional view taken on line 4-4 of Figure 2.

40 Referring to the drawing in detail, the reference character 5 designates the pen cap to which the invention is applied, the cap being of the usual construction, the clip 6

forming the feature of the invention being secured to the cap in any suitable or well known manner.

The clip includes a relatively long arm formed of suitable flexible material and is provided with a head 7, formed in the form of a sphere and at one end thereof, the head 50 being cut away to provide a slot to accommodate the roller 8, which is rotatably supported within the head as by means of the shaft 9, which extends through the head and intersects the slot.

55 As shown, the roller 8 is provided with a plurality of notched portions providing peripheral ribs 10, which ribs or teeth have their side walls tapered so that the edges thereof will bite into the cloth in which the 60 pocket is formed, and firmly support the clip and article.

It is obvious that when the clip is applied, the ribs of the roller 8 will bite into the cloth and permit the device to be readily positioned on the pocket of the user, the ribs causing the roller 8 to roll while the clip and article are being positioned.

Having thus described the invention, what is claimed as new is:

70 In a device of the character described, a relatively long arm having a spherical head formed at one end thereof, said head having a cut out portion, a roller supported by the head within the cut out portion, said roller 75 having a plurality of teeth formed on the periphery thereof, the teeth extending beyond the surface of the spherical head to bite into a supporting element.

In testimony that I claim the foregoing 80 as my own, I have hereto affixed my signature in the presence of two witnesses.

JOSEPH WARREN KESSEL.

Witnesses:

ADOLPH KRAMER,
EDWARD KRAMER.
